UNITED STATES PATENT OFFICE.

WILLIAM A. COWLEY, OF STAMFORD, NEW YORK.

SIDE-HILL PLOW.

SPECIFICATION forming part of Letters Patent No. 242,757, dated June 14, 1881.

Application filed September 11, 1880. (No model.)

To all whom it may concern:

Be it known that I, WILLIAM A. COWLEY, of the village of Stamford, in the county of Delaware and State of New York, have invented a new and useful Improvement in Side-Hill or Reversible Plows, which improvement is fully set forth in the following specification, reference being had to the accompanying drawings.

10 The object of my invention is to provide a means by which the double reversible mold-board of the ordinary side-hill or reversible plow now in common use may be readily and easily detached from its supporting framework, standard, or beam, then reversed and readily, easily, and automatically secured by the reversed edge of the same mold-board to the opposite side of the same standard or beam.

15 In the accompanying drawings, Figure 1 is intended to represent a general or perspective view of the mold-board and beam of the ordinary side-hill plow with the improvement herein specified attached, the beam B and standard, as is usually the case in plows of this description, when made of iron, being constructed in one piece. Fig. 2 represents, in detail, more fully this particular improvement or invention.

20 In my invention, C represents a double-ended lever, in the center of which is a round hole, 30 through which passes a bolt or a short stud, b, upon which the lever may vibrate laterally, and connecting it either to the handles of the plow (which it has not been deemed necessary to show in the drawings) or to the rear end of 35 the beam B, as shown in Fig. 1. At the extremities of this lever are hooks a, which are made to engage at either end with catches d upon the mold-board, thus, when engaged, rigidly holding the mold-board against the standard, whether upon its right or upon its left side. Around the hole in the center of the 40 lever C is a square or slightly lozenge-shaped hub, e, with one projecting corner at the rear acute angle, forming a stop, f. Lying against 45 the opposite right and left sides of the hub e

are two plain flat springs, g, bolted, riveted, or otherwise fastened at their forward ends to and upon opposite sides of the beam or standard B.

In reversing the plow the operator presses 50 with his foot the disengaged end of the lever C, thus liberating the engaged hook a upon its opposite end from the catch d upon the mold-board, and at the same time impelling the lever with sufficient force to cause two of the 55 corners of the square hub e to pass the central point of contact with the two springs g. The closing again of the two springs g will continue the movement of the lever until the end of one of the springs is brought in contact 60 with the stop f upon the hub e, when the hook a upon the opposite end of the lever C will be in proper position to engage with its corresponding catch d upon the reversed edge of the mold-board. The two springs g also firmly 65 hold either of the hooks a and corresponding catches d in engagement until liberated, as above described.

It will be evident that the lever C and the 70 springs g may be placed either over or under or through the handles of the plow, as may be most desirable or convenient, and pins or other projections upon the lever may be used, instead of the hub e, and not change the nature of the invention.

I do not claim as my invention an ordinary 75 double-ended and hooked lever, nor the corresponding catches upon the mold-board, as these have been heretofore in use; but

I do claim as my invention, and desire to secure by Letters Patent—

The double-ended and hooked lever C, having a square hub, e, and stop f, in combination with the springs g upon the beam of the plow, and the reversible mold-board A, having lugs 85 d, substantially as shown and described.

WILLIAM A. COWLEY.
